Primary Examiner — Susan Bennett Hattan*Assistant Examiner* — Marie Fast Horse(74) Attorney, Agent, or Firm — Fish & Richarsson P.C.CLAIM

The ornamental design for a pod for a device, as shown and described.

DESCRIPTION

FIG. 1 is a front, top, and side perspective view of a pod for a device embodying our new design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

The broken lines that cut through the middle of the pod for a device depict break-away lines and form no part of the claimed design.

1 Claim, 4 Drawing Sheets(56)
